AMMUNITION CHUTE

Warren H. Nobles, St. Paul, Minn.

Application October 29, 1948, Serial No. 57,157

4 Claims. (Cl. 193—25)

1

My invention relates to an improvement in ammunition chutes wherein it is desired to provide a chute construction through which ammunition or the like may pass with a minimum of friction.

In the use of weapons which shoot a series of projectiles, it has been found desirable to provide a flexible chute through which the chain of projectiles may be fed. Not only is it necessary for these chutes to be extremely flexible, but also it is essential that the projectiles pass through the chute with a minimum of friction to avoid difficulties in quickly delivering the projectiles to the gun. In my previous patent, No. 2,488,679, for "Flexible chute," I disclosed a chute which was extremely flexible and which included a series of overlapping plates for guiding the projectiles from one chute section to the next. While this previous chute was found extremely advantageous in use, there was in some instances a tendency for the projectile to catch on the supporting edges of these overlapping plates, thus somewhat increasing the force necessary to move the projectiles through the chute. Furthermore, while the chute sections were so constructed to be assembled and disassembled in a relatively short period of time, the detail construction was found to be slightly more complicated than was required to serve the purpose.

The object of the present invention is to correct these slight difficulties encountered in the manufacture and use of my previous chute construction and to provide a simplified construction which may be easily assembled and disassembled when necessary.

A feature of the present invention lies in the provision of a series of chute sections equipped with plates designed to be assembled in overlapping relation so as to provide a continuous guide for shells or other articles and to so support these plates that there is no danger of obstructing the passage of the shells through the chute. The plates include an elongated panel of sufficient length to overlap the next adjacent chute section and this panel is connected to the body of the chute section by rivets or other suitable means which extend through legs on opposite sides of the plate. These legs are so connected with the surface of the plate over which the shells slide that there is no danger of obstructing the free passage of the shell.

An added feature of the present invention resides in the manner in which the various chute sections are connected together. Each chute section is connected to the next adjacent sections

2

by a pair of links arranged in overlapping relationship. These links are connected to the chute sections by a clip having a pair of spring ears which extend through the links. By flexing one or both of these spring ears the links may be detached from any chute section, permitting any section to be quickly removed and replaced.

A feature of the present invention resides in the provision of a link connecting means which includes a clip supported in parallel relation to a body portion of each section, but spaced therefrom. Spring ears are connected in opposed relation to opposite sides of this clip, the ears being bent to underlie the portion of the body to which the clip is attached and to be held against the body under spring tension. Aperature means is provided through the body portion adjacent these ears so that the ears may be flexed out of normal position by a tool inserted through the aperture to permit the links to be detached by sliding the same between the ears and the body portion.

These and other objects and novel features of my invention will be more clearly and fully set forth in the following specification and claims.

In the drawings forming a part of my specification:

Figure 1 is a top plan view of a series of chute sections showing the construction thereof.

Figure 2 is an end view of the chute sections.

Figure 3 is a sectional view through one of the chute sections, the position of the section being indicated by the line 3—3 of Figure 1.

Figure 4 is a longitudinal section through a portion of the chute, the position of the section being indicated by the line 4—4 of Figure 1.

Figure 5 is a sectional view longitudinally through the chute, the position of the section being indicated by the line 5—5 of Figure 1.

Figure 6 is a perspective view, partially in section showing the manner in which the extension links are connected to the various chute sections.

Figure 7 is a view similar to Figure 6 showing the manner in which the individual links may be disconnected from a chute section.

Figure 8 is a perspective view of one of the plates mounted on each chute section to overlap the next adjacent section.

Figure 9 is a perspective view of a second plate which is mounted on each chute section to overlap the next adjacent section.

Figure 10 is a perspective view of a detail portion of the chute sections.

The chute A includes a series of sections B which are connected together so as to produce a flexible chute. In general my chute is similar to that illustrated in my previous application above identified, but is somewhat advantageous thereto.

Each chute section includes a U-shaped end portion designed to enclose one end of a shell such as C. The U-shaped end sections 10 include a top flange 11, an end wall flange 12, and a bottom flange 13. The bottom flange 13 is provided with an off-set socket 14 therein for accommodating one end of a rod 15. The rod 15 is preferably pressed into the socket 14 or is otherwise attached thereto and in the construction illustrated the rod 15 rotates with the socket 14.

The opposite end member 16 includes a top flange 17, an end wall flange 19 and a bottom flange 20. The bottom flange 20 is provided with an integral socket comprising a bearing portion 21 and a socket portion 22 arranged in spaced relationship. The bearing portion 21 is provided with an aperture 23 therethrough through which the rod 15 may extend. The socket portion 22 is provided with a recess or aperture 24 extending partially therethrough in which the end of the rod 15 is rotatably supported. A collar 25 is frictionally engaged on the rod 15 between the socket portions 21 and 22 and holds the rod 15 from longitudinal movement relative to these socket portions. Obviously the rod 15 may rotate within the socket portions 21 and 22 to permit rotation of the end element 16 relative to the end element 10.

As best illustrated in Figures 2 and 3 of the drawings the flange 11 is provided with a groove 26 in its under-surface, this groove having a central portion 27 which is slightly deeper than the remainder of the groove. A similar groove 29 is provided in the end wall 12 and another similar groove 30 is provided in the bottom flange 13. The top flange 17, end wall flange 19 and bottom flange 20 of the end member 16 are likewise provided with similar grooves 31, 32, and 33, respectively. These grooves are all identical in construction and include similar elements. The various grooves are provided for the purpose of containing section connecting elements and overlapping guide plates which will be later described in detail.

Each of the grooves thus described is bridged by a pair of elements used either for connecting adjacent chute sections or providing a smooth slide for the ammunition. As best illustrated in Figures 2, 3, 6, and 7 of the drawings the flange 11 is provided with a plate 34 bridging the grooves 26 and 27. This plate 34 is best constructed as illustrated in Figure 10 of the drawings and includes a pair of oppositely disposed ears 35 and 36 which extend upwardly from opposite sides of the plate and which include opposed flanges 37 and 39 respectively, which extend into close proximity with one another. The ears 35 and 36 are formed of material possessing a certain degree of resilience so that the flanges 37 and 39 may be bent toward the body of the plate 34 without permanently deforming the same. Apertures 40 are provided near opposite ends of the plate for accommodation of the fastening means which will be later described. Also bridging the grooves 26 and 27 and underlying the plate 34 I provide a plate 41 which is designed to extend into overlapping relation with the next adjacent section B. The plate 41 includes a generally flat upper surface which is bent out

of the plane of the rest of the plate at one edge 42 as best illustrated in Figure 8 of the drawings. The plate 41 is supported by opposed legs 43 which are connected with oppositely extending feet or flanges 44. Apertures 45 are provided in the flanges 44 to accommodate fastening means, the apertures 45 being spaced apart a distance equal to the spacing of the apertures 40 in the plate 34.

10 When legs such as 43 are bent downwardly from a plate such as 41, the bend usually occurs at a point slightly spaced from the edge of the plate. As a result, small rounded shoulders are produced at each side of the leg, these shoulders being flush with the surface of the plate. From time to time these shoulders catch or dig into articles passing through the chute, increasing the pull required to draw the articles through the chute and in some cases damaging the articles.

15 20 One of the primary objects of this invention is to eliminate these shoulders.

It will be noticed that the upper edges of both of the parallel legs 43 are rounded so that the edges of these legs are somewhat below the surface of the plate 41. The rounded edges of the legs adjacent the end 42 of the plate 41 curve together with the body of the plate. The other ends 46 of the legs 43 are connected to the plate 41 by curved edges which are below the level 25 30 of the plate 41. Thus an object passing over a series of plates 41 can not engage the corners between the plates 41 and the legs 43 and therefore can not interfere with the proper movement of ammunition or other material through the 35 chute.

As best illustrated in Figures 3, 6, and 7 of the drawings an aperture 47 is provided in the flange 11 in alignment with the opposed flanges 37 and 39 of the plate 34. As a result a tool D may be 40 inserted through the aperture 47 and bear against either of these flanges 37 or 39 to bend this flange downwardly. Normally, however, these flanges 37 and 39 engage against the flange 11 at the base of the groove 27.

45 A pair of rectangular links 49 are connected to the plate 34 in the manner illustrated in Figures 6 and 7. Each link 49 is provided with substantially parallel side members 50 and 51 which are connected by cross members 52 and 53 at a 50 point spaced from the ends thereof. The cross member 52 of one link and the cross member 53 of the next adjacent link are positioned in the groove 26 between the body of the plate 34 and the flanges 37 and 39 of the ears 35 and 36. 55 These links 49 are longitudinally slidable relative to the sections, the amount of the sliding movement being the difference in the width of the cross members 52 and 53 and the distance between the ears 35 and 36. As the side members 60 50 and 51 of the links project beyond the cross members 52 and 53, these longitudinal members are always in overlapping relation, thus preventing the ends of the links from abutting to 65 prevent the slidable movement of the links in one direction.

The links 49 are disengageable from the flange 11 in the manner best illustrated in Figures 6 and 7 of the drawings. In Figure 6 of the drawings the tool D is shown flexing the extremity of the flange 39 downwardly toward the surface of the plate 34. While thus depressed the cross member 52 of one of the links 49 may be interposed between the free end of the flange 39 and the flange 11 as illustrated in Figure 7 of the drawings, whereupon this link 49 may be with-

5

drawn between the flange 39 and the flange 11 and disengaged from the section illustrated.

In a similar manner the opposite link may be disengaged from the section to which it is attached by bending the flange 37 downwardly toward the plate 34 and engaging the link end 53 between the flange 37 and the flange 11. When interposed between these elements the link may be moved longitudinally to disengage the link from the section.

The links 49 which connect the flanges 11 have been described in detail. A similar structure is provided to connect various others of the flanges. As many of these connecting structures are identical in form the parts thereof have been designated by the same identifying numerals as those used in connecting the flange 11. It should be noted also that the plates 34 and 41 which hold the links in place on the flange 11 are connected to the flange 11 by rivets 54 or other suitable attaching means.

From the foregoing description it will be obvious that a set of plates 34 and 41 are likewise connected to the flange 12 of the end section 10 by rivets 55 or other suitable connecting means. The plates 34 and 41 enclose links 49 located in the slot 29, the various elements being connected in the manner previously described. An aperture 56 through the flange 12 permits the tool D to be inserted to detach any of the links 49 from the plate 34 in the manner previously described.

A similar set of plates 34 and 41 are connected to the flange 13 of the end section 10 by rivets 57 or the like. The plates 34 and 41 detachably connect links 49 which are slidable in the slot 30. An aperture 59 through the flange 13 permits the tool D to engage the flanges 37 and 39 of the plate 34 so that the rings may be detached when desired.

The flange 19 or end wall of the end 16 likewise supports a pair of plates 34 and 41, these plates being connected by rivets 60. The plates 34 and 41 act to hold in overlapping relation a pair of links 49 which act to connect the end section 16 of one section B to the end section 16 of the next adjacent section B. An aperture 61 is provided through the end wall 19 so that the tool D may be used to flex the flanges 37 and 39 of the plate 34 in the event the links 49 connecting thereto are to be removed.

The length of the legs 43 on the plate 41 depends upon the diameter of the part of the shell C engaged. It will be noted that the two ends of the chute are of substantially the same size, but one end 62 of the shell C is of smaller diameter than the opposite end 64 thereof. As a result the supporting legs on the plates must be varied in length to position the plates closer together on the end section 16 to accommodate the smaller diameter of the shell C. Obviously if the chute is designed to handle shells or other articles which are of similar thickness throughout their width, all of the plates used may be of similar size and shape.

In Figure 9 of the drawings I disclose a plate 65 which corresponds to the plate 41 previously described and which may be substituted therefor to shorten the distance between these plates at one end of the sections B. The plates 65 are substantially flat throughout the major portion of their length, but are bent at one end 66 out of the plane of the remainder of the plate as illustrated. Legs 67 are connected to opposite sides of the plate 65 near the end 66 thereof and flanges or feet 69 are provided on the legs 67 to

6

provide a means of attaching the plates to the end sections 16. The flanges 69 are provided with apertures 70 therethrough for accommodating the fastening rivets or other attaching means.

As previously described in conjunction with the description of the plate 41, the legs 67 are connected to the plate 65 along curved lines of connection 71. The connecting line between each leg 67 and the bent end 66 of the plate 65 follows the curvature of this bent end. The other edge 72 of each leg 67 is also curved toward the foot 69 to produce rounded connecting portions 73 between the legs 67 and the plate 65. Thus the shoulders normally formed in bending the legs 67 into parallel relation are eliminated. As previously described these shoulders usually extend flush with the surface of the plate 65 and tend to catch or dig into articles passing over the plates 67. By recessing the connecting portions and eliminating the flush rounded shoulders the efficiency of the chute is greatly increased.

The manner in which the plates 65 are used is best illustrated in Figures 2, 3, and 5 of the drawings. As indicated in these figures a plate 34 overlies the groove 31 in the flange 17 of the end section 16 and a plate 65 overlies the plate 34. Rivets 74 connect the plates 34 and 65 to the flange 17. A pair of links 49 are connected in overlapping relation between each plate 34 and the adjacent flange 17 to connect each flange 17 to the corresponding flange 17 of the next section B. An aperture 75 is provided through the flange 17 to provide access to the flanges 37 and 39 of the plate 34 in the event the links 49 are to be disengaged.

A similar arrangement is provided on the flange 20 of the end member 16. A plate 34 and a plate 65 are secured by rivets 76 to the flange 20 to overlap the groove 33. Links 49 are connected in overlapping relation in the groove 33 between the plate 34 and the flange 20. An aperture 77 is provided in the flange 20 to admit the tool D and to allow flexing of a flange 37 or 39 to permit removal of one or both of the overlapping links 49.

In accordance with the patent statutes, I have described the principles of construction and operation of my flexible chute construction, and while I have endeavored to set forth the best embodiment thereof, I desire to have it understood that obvious changes may be made within the scope of the following claims without departing from the spirit of my invention.

I claim:

1. A flexible chute including a series of sections, each of said sections being connected to the next adjacent section by a pair of overlapping links, said links being slidably supported between a portion of the section and a plate secured to the section, said plate having a pair of opposed hook shaped resilient ears extending therefrom in opposed relation and terminating adjacent said body, each of said hook shaped ears extending through one of said links, said ears being resiliently bendable toward the plate for permitting disconnection of the link through which the ear extends.

2. A flexible chute including a series of sections, means connecting said sections for relative movement therebetween, a plate on each section designed to overlap a similar plate on the next adjacent section, a body portion on each section to which said plate is secured, a pair of substantially parallel legs on each plate for spacing the plate

from the body portion, means for securing said legs to the body portion, and a curved fold line between said legs and said plate, the ends of said fold line terminating beneath the plane of the plate.

3. The structure described in claim 2 in which one end of the plate is bent out of the plane of the liner of the plate along said line of fold.

4. A flexible chute comprising a series of sections, means flexible connecting said sections together, a plate on each section extending in overlapping relation with a similar plate on the next adjacent section, said plates being substantially flat throughout the major portion of their length and having an end bent toward the adjacent portion of the section, legs on opposite sides of said plate for spacing the plate from the portion of the section to which the plate is attached, feet on

said legs, means for anchoring said feet to said section, and a rounded line of connection between said legs and said plate, said rounded line terminating substantially below the level of the plate at each end thereof and being substantially flush with the surface of the plate intermediate the ends.
